(57) **CLAIM**

The ornamental design for a battery compartment for a rifle scope, as shown and described.

DESCRIPTION

FIG. 1 is a left side perspective view of the battery compartment of our new design shown mounted on a rifle scope;

FIG. 2 is a right side perspective view of the battery compartment of FIG. 1 with a portion of the rifle scope on which the battery compartment is mounted;

FIG. 3 is a left side front perspective view of the battery compartment of FIG. 1;

FIG. 4 is a top plan view of the battery compartment of FIG. 1;

FIG. 5 is a bottom plan view of the battery compartment of FIG. 1;

FIG. 6 is a left side elevation view of the battery compartment of FIG. 1;

FIG. 7 is a right side elevation view of the battery compartment of FIG. 1;

FIG. 8 is a rear elevation view of the battery compartment of FIG. 1; and,

FIG. 9 is a front elevation view of the battery compartment of FIG. 1.

The rifle scope body shown by dashed lines in FIGS. 1 and 2 is for illustrative purposes only and forms no part of the claimed design.
